REFRIGERATION SYSTEM

Harry A. B. Brown, San Francisco, Calif.

Application May 1, 1939, Serial No. 271,052

4 Claims. (Cl. 62—91.5)

This invention relates to a refrigeration system which uses a fluid refrigerant and in which the motive power for actuating the flow of the refrigerant to the point or points where evolving is to be effected by transfer of heat to the refrigerant, is independent of mechanical or electrical power. Another object is an improved, economical system of refrigeration in which the refrigerant, such as ethyl chloride, or other fluid having a relatively low freezing point is moved in a closed circuit including a heat exchange coil or the like, and is cooled before movement into such coil by solid CO₂, or dry ice, with the motive power for causing the movement being supplied by CO₂ gas pressure resulting from sublimation of the dry ice caused, principally, by the transfer of heat units from the refrigerant to the dry ice during movement of the refrigerant in said circuit. Another object is improved apparatus employed in my system of refrigeration, which apparatus is simple, dependable, and economical to make. Other objects and advantages will appear in the description.

In the drawings,

Fig. 1 is a semi-diagrammatic view, partly in section, illustrating my improved system.

Fig. 2 is a sectional view of a portion of my apparatus, certain elements being shown in elevation.

Fig. 3 is an enlarged elevational view of one of the elements of the portion illustrated in Fig. 2.

Fig. 4 is a sectional view along the line 4—4 of Fig. 3.

Fig. 5 is a sectional view along the line 5—5 of Fig. 3.

Fig. 6 is a sectional view along the line 6—6 of Fig. 3.

Fig. 7 is a sectional view along line 7—7 of Fig. 3.

Fig. 8 is a diagrammatic view of a modified form of the invention.

In detail, referring to Fig. 1, I show an air tight tank 1, containing dry ice 2, which tank is provided with an inner bottom 3 and an outer bottom 4, thus forming a double bottom with a space 5 between said inner and outer bottoms with an inlet conduit 6 opening into said space at one point and an outlet conduit 7 communicating at one end with said space at another point, the inlet and outlet openings into said space being preferably at opposite sides of the tank so that a liquid entering the space from the inlet opening will pass over substantially the full area of space and out through the outlet.

The inlet and outlet conduits with the space 5 thus virtually constitute one continuous conduit for a liquid refrigerant having a low freezing point, such as ethyl chloride, "Freon," sodium chloride, and the like, and the heat unit in the refrigerant flowing from the inlet to the outlet between the bottoms 4, 5, will be readily absorbed by the dry ice in container 1. The walls of container 1 are, of course, preferably heat insulated in the usual manner, and a closure 8 is provided for filling the container with dry ice, and a pressure relief valve 9 is also provided for preventing dangerous pressure in the container by reason of the CO₂ gas.

Conduit 7 leads to a conventional cooling or heat exchange coil 10 positioned in the area to be cooled. If in a car or compartment, the coil is preferably at the top of the same, or said cooling coil may obviously be placed wherever a cooling result is desired.

A continuation 11 of the cooling coil opens into a closed tank or receptacle 12 at the upper end of the latter, and a pipe 13 opens into the bottom of said tank, the opening being preferably covered by a screen 14.

The pipe 13 extends downwardly from tank 12 and is provided with a check valve 15, and a manually operated cut-off valve 16, and continues past the cut-off valve and through a cover 17 (Fig. 2) into the upper portion of a container 18. The continuation from the cut-off valve into the container 18 may be provided with the conventional union for disconnecting the portion extending into said receptacle from the conduit 13 to facilitate removal of cover 17 from the container.

The cover 17 also supports on its underside a cylindrical, open-ended valve casing 19 secured to the cover in any suitable manner, such as by screws 20 or the like, and within said casing a cylindrical slided, hollow, open-ended, valve member 19' disposed co-axially with the casing and rotatable therein about its axis. The cylindrical wall of casing 19 is formed with a pair of ports 21, 22 (Figs. 3 to 5) and a pipe 23 extends between port 21 and a point in one of the walls of tank 1, preferably somewhere above the bottom of said tank, while an exhaust pipe 24 communicates between port 22 and the atmosphere.

The ports 21, 22 are at points in longitudinal alignment in direction axially of the axis of the casing, and valve 19' is also ported at 21', 22', which ports 21', 22' are similar in size to ports 21, 22 and are positioned so that port 21' will register with port 21 in one position of the valve,

while the port 22 will be closed by a wall of the valve, but upon rotating the valve a predetermined distance about its axis, the port 22' therein will register with port 22 and ports 21' will move out of registration with port 21 to close port 21 by the wall of said valve adjacent said port 21'. The movement of valve 18' is an oscillating one, rather than full rotation of the valve, so that about a quarter of a turn of the valve in opposite directions will bring ports 21, 21' into registration at one end of the movement and ports 22, 22' will be in registration at the other end of said movement, but ports 21, 21', and 22, 22' will not be in registration at one time, as will hereinafter be described.

In pipe 23 is a check valve 25, and between check valve 25 and tank 1 is a thermostatically controlled valve 26, which latter valve is actuated by a conventional thermostatic device 27 positioned adjacent the cooling coil 10 or in the area to be cooled.

From the foregoing, it is seen that when ports 21, 21' are in registration, and valve 26 is open, communication is established between container 18 and tank 1.

For convenience in removal of cover 17 with the valve assembly connected thereto, a conventional union may be in the section of pipe 23 between check valve 25 and the cover.

The conduit 6 has a check valve 28 therein and said conduit communicates between the space 5 between bottoms 3, 4 of the tank 1 and the bottom of container 18, said check valve 28 permitting flow of liquid from container 18 to space 5, but preventing back flow.

Referring to Figs. 2 to 6, the valve assembly within the container 18 includes the valve casting 19 and valve 18' with ports 21, 21', 22, 22', as already described. The rotation of valve 18' is effected by a rotary shaft 29 in axial alignment with the central axis of the valve, one end 29' of which shaft projects within an extension 38 of valve 18' that projects outwardly of one end of casing 19. The end 29' carries pin 31 projecting radially thereof and into an arcuate slot 32 extending circumferentially in said extension 38.

Shaft 29 also carries a disk 33 at a point spaced outwardly of the extension 38 of the valve, which disk is free for rotation on shaft 29, and carries an arm 34 extending radially outwardly therefrom, the outer end of said arm having a hollow ball float member 35 secured thereto.

The disk 33 is formed with a recess 36 opening outwardly at a point around the periphery thereof (Figs. 3, 6) in which recess one end of a pin 37 is received. The pin 37 extends axially of shaft 29 and is secured at its opposite end to the outer end of a short arm 38, the inner end of said arm being secured on the end of shaft 29 that is remote from valve 18'. The pin 37 extends through said arm to project outwardly therefrom at the side thereof opposite disk 33, as at 38 (Figs. 3, 6), and a tension coil spring 40 is secured at one of its ends to end 38 of the pin, the opposite end of the spring being secured to cover 17 in any suitable manner at a point 41 directly over the axis of shaft 29 and in a plane perpendicular to the plane of cover 17.

Between arm 38 and disk 33, and between disk 33 and valve 18' are bearings 42 rotatably supporting the shaft 29 and suspending the shaft from the cover. The bearing adjacent arm 38 projects at its outer end, laterally (relative to the shaft 29), a sufficient distance to be engaged by

the portion of pin 37 that extends from arm 38 to recess 36 when the shaft is rotated in one direction, thus forming a stop against further rotation of the pin in said one direction, and when 5 the shaft is rotated in the opposed direction the outer end of the bearing likewise forms a stop against further rotation in said other direction. The action of spring 40 during such rotation is to yieldably resist the rotation in one direction or the other until the arm 38 moves across the central axis of the shaft, and thereafter the spring tends to forcefully rotate the shaft during the remaining movement.

The arm 34 that carries the ball float 35 also 15 carries a disk valve 43 on its upper side, which disk valve is adapted to closely seat over the end of pipe 13 that extends through the cover 17 into container 18 when the container is substantially filled with liquid and the ball float is in its highest position (Fig. 2).

When the container 18 is filled, and ball float 35 is in the position illustrated in Fig. 2, the valve 18 is in a position in which ports 21, 21' are in registration, and in which CO₂ gas from tank 1 can flow into container 18, provided the thermostatic valve 26 is open. Also, in this position, no liquid can flow into container 18 from the tank 12, since valve 43 closes the pipe 13 against such flow. However, upon lowering of the level of 25 liquid in container 18, the ball float 35 will fall, causing rotation of shaft 29 and also rotation of the disk 33, through the one end wall of the recess 36 in disk 33 being in engagement with the pin 37. The slot 32 in extension 38 of the valve 18' extends circumferentially thereof and pin 31 that extends into said slot will be moved from one end of the slot to the other as the shaft 29 revolves under the influence of the descending ball float. When pin 37 is moved across the 30 axis of shaft 29, the pin 37 will be moved into engagement with the said other end of slot 32 and then spring 40 will react to quickly rotate the shaft around a sufficient distance to quickly rotate the valve 18' from position with ports 21, 21' in registration with each other and to close port 21. Upon liquid flowing into container 18 through pipe 13, the ball float will rise, and the 35 valve assembly will be restored to the position indicated in the drawings.

From the description thereof thus far, it is seen that the cooling coil and its extension 11, the tank 12, conduit 13, container 18, conduit 6, space 5 and conduit 7 make up a closed conduit, of which the tank 12, container 18 and space 5 40 may be considered enlarged portions thereof. Also considering that the liquid refrigerant substantially fills the closed circuit as described to the level of the top of tank 12, it will be obvious that there will be a gap in such circuit that includes part or all of the cooling coil 10, or at 45 least some of the circuit above the level of liquid in said tank 12.

In operation, with the circuit filled to the extent described above, and with dry ice in the container 1, it is obvious that a CO₂ gas pressure in container 1 will be built up, the sublimation of the dry ice to produce said gas being more or less controlled by the temperature of the liquid refrigerant in space 5 between the bottoms 3, 4. Upon a predetermined rise in temperature in the area to be cooled, the thermostatic device 27 will 50 open valve 26 permitting the CO₂ gas to flow into container 18, thus building up a pressure over the liquid in said container 18 and forcing the cooled refrigerant in space 5 into the cooling coil

18. The check valve 18 in pipe 13 closes against the flow of liquid into container 18 until such time as the gas pressure in container 18 is relieved, hence as the liquid is forced out of container 18 and into the cooling coil, the float 35 will drop, rotating valve 19' to position in which ports 22, 22' are in register, when the gas in container 18 will be exhausted and the liquid from tank 12 will flow into container 18 causing the float 35 to rise and thereby actuate valve 19' to rotate the latter back to a position placing ports 21, 21' in register and closing port 22. This action will be repeated as long as the thermostatic valve 28 is held open by the thermostat.

In actual practice, the system will operate satisfactorily at very low gas pressure, particularly where care is taken in the installation to keep the upwardly extending length of conduit 1 relatively short. The application of gas pressure in container 18 direct to the body of the refrigerant, rather than by indirect transmittal of power to mechanical means, such as pistons, diaphragms, etc., eliminates the complications that are common to such means, and also enables circulation of the liquid refrigerant under less gas pressure than is required where such means may be employed. With the use of such lowered pressure, objectionable carbonization of the liquid refrigerant is avoided, and the gas that is discharged from the system, other than may be discharged in the event of actuation of the pressure relief valve, is only that amount used periodically after each movement of the liquid refrigerant from container 18 to the cooling coil.

Another advantage in my invention is the almost complete elimination of mechanical parts that might cause a failure in operation, which is a particularly important feature in cars, and the like, where servicing facilities are limited, but where a failure of operation would result in heavy losses in products requiring a low temperature for preservation thereof.

Heretofore, efforts towards accomplishing the desired results of this invention have involved the use of motors, mechanical pumps, diaphragms, pistons or the like, and also attempts have been made to cause movement of secondary liquid refrigerant by CO_2 gas by causing the gas to bubble through a column of such refrigerant for agitating the liquid to the point where it will be caused to overflow from the column on irregular splashes. This latter method is objectionable due to its low cooling efficiency and to the fact that carbonization of the liquid occurs to an undesirable degree and to the fact that the escape of gas is practically continuous, thus making for high operating costs.

In Fig. 8, I show, diagrammatically, a modified form of the invention, in which the liquid refrigerant is passed directly into the dry ice container, so that the latter forms part of the closed circuit for the liquid. No double bottom is used. The outlet conduit 1' from the bottom of tank 1' has a check valve 44 therein, which conduit leads to cooling coil 18', and from 18' a continuation 11' thereof, extends directly into the top of container 18', which latter contains the valve elements identically as described with reference to the preferred form of the invention, except that valve 43 or the equivalent thereof, is omitted. From the foregoing, it is seen that the tank 12 as shown in Fig. 1, is omitted.

From the container 1' the gas inlet pipe 23' communicates between the upper portion of tank 1 and the valve mechanism in container 18', and

exhaust pipes 24' also communicates with said valve in the same manner as shown in Fig. 1 and described in Figs. 3 to 7. The outlet conduit 8' from the bottom of tank 18' communicates between tank 18' and the bottom end of container 1' at a point just above the bottom of the container 1', check valve 48 being in said pipe. In conduit 7' just in advance of the cooling coil 18', I provide a thermostatically actuated valve 28' adapted to be actuated by a thermostat device 27' for opening the line 7' to flow of liquid into the cooling coil upon a rise in temperature at device 27'.

In operation, assuming the liquid is all in the bottom of container 1', and valve 28' is open. The gas in container 1' is not free to pass into container 18' through conduit 23', since port 21 is closed, hence the pressure on the liquid in container 1' will force the same through conduit 7' into the cooling coil 18' and from thence into container 18', filling the container and causing the float therein to rise until float actuated valves are moved to close exhaust 24' and to open conduit 23' to flow of gas into container 18', thus equalizing the gas pressure on the liquid in container 18' and in container 1', thereby permitting the liquid in container 18' to flow by gravity into container 1'. This results in the float in container 18' falling and opening the exhaust port in container 18' and closing port 21' thereby restoring the elements to the position above described at the commencement of the operation. This cycle is then repeated as long as valve 28' is open, but is discontinued during the period when valve 28' is closed.

The dry ice 2' in the above container 1' is supported on a pan or tray 46 supported above the bottom of the container, as by legs 47 or in any other suitable manner. This pan is preferably of sufficient strength to support the dry ice, but of appreciably lesser thickness than is required by the walls of the container to hold the gas pressure developed in the container, hence there is a more rapid transfer of heat from the fluid to the dry ice through the relatively thin walls of said pan. The level of the liquid refrigerant in the bottom of the container 1', even when all of the refrigerant is therein, is preferably below the upper edges of the side of said pan 46, and in operation the level is preferably always in a plane somewhere above the level of the bottom of the pan so as to maintain a constant heat transfer relationship between the dry ice and the liquid through the walls of the pan. Since the sides of the pan are spaced at one or more points or at all points therearound from the side walls of the container, the gas pressure developed in the pan is always effective on the surface of the liquid refrigerant in the container 1'. In describing the pan walls as spaced from the sides of the container 1' to admit the gas pressure directly into the liquid refrigerant, it is to be understood that perforations may be provided in the pan sides or in a flange connecting between the upper edges of the pan sides and walls of the container, without invention, since the basic idea is to permit gas pressure in the container to be effective on the surface of the liquid refrigerant in said container.

The advantage of the above construction is apparent when it is considered that in using a double bottom, the metal of the inner bottom must be very heavy to withstand the gas pressure, thus reducing the rate of transfer of heat from the liquid refrigerant to the dry ice. But it

is to be understood that the device of Fig. 8 is intended for relatively low gas pressure to avoid objectionable carbonization of the liquid refrigerant, while the device of Fig. 1 may be used for higher gas pressure.

The pan 48 is preferably imperforate below the maximum level of the liquid refrigerant in container 1', but may be made perforate if it is found desirable to obtain a lower temperature in the liquid refrigerant.

Having described my invention, I claim:

1. In a refrigeration system, a primary refrigerant composing a body of solid CO₂, a container in which said body is enclosed fitted with a hollow bottom having one of its walls disposed in heat exchange relationship with the said CO₂ and supporting the solid CO₂ thereon, an inlet and an outlet to the space between the walls forming said hollow bottom, a cooling coil, a first conduit leading from said outlet to one end of said cooling coil and a second conduit leading from the opposite end of said cooling coil to said inlet, said second conduit including a circulating control chamber, a gas pressure line communicating between said chamber and said container for conducting CO₂ gas resulting from evaporation of said solid CO₂ to said chamber, a float valve in said chamber arranged and adapted to control the flow of said liquid through the chamber toward said inlet, and means including the gas pressure in said gas pressure line and the liquid in said chamber arranged and adapted to actuate said float valve for closing and opening said second conduit to flow of liquid to said inlet.
2. In a refrigerating system, a primary refrigerant comprising a body of solid CO₂, a double walled container in which said body is enclosed including a passageway defined by the double walls of said container, one of which walls is disposed in direct heat exchange relationship with said body of CO₂ for cooling, said passageway having an inlet and an outlet for the liquid refrigerant, a closed conduit connecting the inlet and outlet, said conduit including a cooling coil and a circulating control chamber and a gas pressure line connecting said container with said chamber for conducting CO₂ gas from the container to the chamber, a rotary float-actuated

valve in said chamber arranged and adapted to control the flow of said liquid through the chamber, a float connected with said valve, and means including the liquid refrigerant and the gas pressure in said chamber adapted to actuate said float and valve for opening and closing said conduit to the flow of the liquid.

3. In a refrigeration system, a primary refrigerant comprising a body of solid CO₂, a container in which said body is enclosed fitted with a hollow bottom having one of its walls disposed in heat exchange relationship with the said solid CO₂, and supporting the solid CO₂ thereon, an inlet and an outlet to the space between the walls forming said hollow bottom, a cooling coil, a first conduit leading from said outlet to one end of said cooling coil and a second conduit including a storage tank for said liquid refrigerant, a circulating air tight chamber, a gas pressure line connecting said chamber with said container, a rotary snap-acting valve in said chamber adapted to oscillate for alternately connecting said chamber to the said gas pressure line and to the atmosphere at opposite ends of its oscillatory movement, a float connected with said valve, and means including the gas pressure in said gas pressure line and the liquid in said chamber and said float arranged and adapted to actuate said valve for closing and opening said second conduit to flow of liquid to said inlet.

4. In a refrigerating system, a primary refrigerant comprising a solid body of CO₂, a container in which said body is enclosed including a passageway through the container with an inlet and an outlet thereto for the liquid refrigerant, a cooling coil, a first conduit leading from said outlet to one end of said cooling coil and a second conduit leading from the opposite end of said cooling coil to said inlet, including two chambers only, a gas pressure line communicating between one of said chambers and said container, a float valve in one of said chambers, and means including said liquid refrigerant and gas pressure in said gas pressure line for alternately opening said valve to said gas pressure line and to the atmosphere to cause flow of the refrigerant to said inlet.

HARRY A. B. BROWN.
